UNITED STATES PATENT OFFICE.

ALBERT E. BERDON, OF INDIANAPOLIS, INDIANA.

ELECTROMAGNETIC STRUCTURE.

1,066,721.

Specification of Letters Patent.

Patented Feb. 3, 1914.

Application filed May 10, 1913. Serial No. 766,878.

To all whom it may concern:

Be it known that I, ALBERT E. BERDON, citizen of the United States, residing at Indianapolis, in the county of Marion and State of Indiana, have invented a certain new and useful Improvement in Electromagnetic Structures, of which the following is a full, clear, concise, and exact description, reference being had to the accompanying drawings, forming a part of this specification.

My invention relates to electro-magnets and has for its main object the construction of a magnet in which the armature will cause such a redistribution of the magnetic flux to effect the desired operation of the armature.

As the invention is embodied, to suit a given purpose such as that set forth in my co-pending application Serial No. 763,874, filed May 10, 1913, the armature upon its slightest movement consequent upon magnetic attraction immediately commences and rapidly continues the redistribution of the flux until the armature has completely changed its position in response to its magnetic attraction whereby a rapid and complete closing stroke of the armature is assured after the initial unbalancing of the flux by the armature has been effected, the tendency of the armature to continue the stroke upon which it has commenced being so strong that it will take its full movement even though the initial magnetizing force required to start the movement is largely reduced.

My invention has other characteristics and its various characteristics will be fully set forth by reference to the preferred embodiment thereof shown in the accompanying drawings and in which—

Figure 1 is a plan view; Fig. 2 is a view on line 2 2 of Fig. 4; Fig. 3 is a view on line 3 3 of Fig. 4; Fig. 4 is a side view; Fig. 5 is a view on line 5 5 of Fig. 4; Fig. 6 is a view on line 6 6 of Fig. 1; Fig. 7 is a detail of some of the parts as they appear in Fig. 4; Fig. 8 is a view on line 8 8 of Fig. 4; Fig. 9 is a view on line 9 9 of Fig. 4; and Figs. 10 and 11 are diagrams illustrating the magnetic flux.

Like parts are indicated by similar characters of reference throughout the different figures.

There is preferably no permanent mag-

net portion in the magnet structure, the winding core 1 being preferably of soft unlaminated iron having soft iron polar extensions 2 and 3 secured to its ends by means of screws 4, these soft iron polar extensions 60 extending laterally of the core for a sufficient distance upon each side of the core to afford proper limits to the magnet winding space and each being inturned in approaching directions upon one side of the core as indicated at 5, a suitable gap intervening between the inturned polar extension ends there to constitute a gap in the magnetic circuit. This gap is bridged by a soft iron armature 6 whose lower face is formed 70 with a rounded fulcrum ridge 7 affording a rolling contact between the armature and one of the polar extensions 3 upon which the armature is supported adjacent the gap between the polar extensions. The fulcrum ridge 7 is located substantially midway between the ends of the armature 6 whereby the armature is caused preferably to overlie substantially all of the insetting extension of the polar extension 3 upon which the armature is mounted, the other end of the armature overlying a sufficient portion of the insetting extension of the other polar extension 2 to enable the proper passage of the magnetic flux. In the absence of sufficient tractive effort between the polar extension 2 and the armature 6, a spring 8 operates to draw the right hand end of the armature downwardly until the non-magnetic stop 9 engages the polar extension 3. When the magnetic attraction is sufficient, the force of the spring 8 is overcome to move the armature in a counterclockwise direction, the extent of movement in this direction being limited by a stop 10 of non-magnetic material adapted 80 for engagement with the polar extension 2. The force of the spring is regulated by a horizontally adjustable screw 11 working upon the adjacent and inclined end of the spring 8. The spring operates upon the armature through the intermediation of the strut 12 swingingly connected at its upper end with the armature and at its lower end with a spring tongue 13 projecting upwardly from and being integrally formed 105 with the spring 8.

The flux set up within the magnetic circuit established by the elements 1, 2, 3, 6 and 7 is diagrammatically indicated in Figs. 10 and 11 by the flux lines having the arrow 110

heads pointing a direction of flux. The fulcrum ridge 7 is integrally formed with the armature 6 and has magnetic contact with the polar extension 3, the lines of force having one distribution at the armature when the armature is unattracted and another distribution when the armature is attracted, the portions of the lower armature face being desirably angularly related to 10 permit the armature to swing and to permit the flux to change its distribution to control the movement of the armature. When the armature is unattracted the flux upon the right of the fulcrum 7 is substantially evenly distributed between the polar extension 3 and the right hand portion of the armature but when the armature is magnetically shifted in position the air gap between the armature and the polar extension 15 supporting the same will flare toward the right, this flaring progressively increasing as the armature continues to move in response to its magnetic attraction whereby the magnetic reluctance at its right hand air gap increases and progressively increases toward the right hand limit of the armature so as to effect a progressively increasing concentration of the lines of force toward and at the fulcrum ridge thereby progressively to reduce the magnetic pull upon the 20 right hand end of the armature as the armature is moving to its magnetically attracted position whereby the flux across the air gap at the left hand end of the armature, as it is progressively shortened, may cause the 25 more rapid positive closing movement of the armature, the magnetic opposition to such closing movement at the right hand end of the armature being rapidly and progressively decreased as will be understood for 30 reasons above explained and owing also to the lengthening of the portions of the lines of force that span the progressively increasing air gap at the right hand end of the armature. Thus all the flux traverses the gap at the left hand end of the armature while the portion which traverses the gap at the right hand end of the armature progressively decreases as this latter gap is widened, 35 a result which is rendered possible owing to the reduction of magnetic reluctance at 7 where a path is afforded for increasing flux diverted therethrough owing to the increasing reluctance at the right of the armature. In other words there is but one 40 flux path at the left of the armature and there are two flux paths at the right hand portion of the armature, one of these latter two flux paths including the fulcrum 7 and the other including the right hand air gap, these two flux paths thus being in shunt relation with each other and each in serial relation with the path at the left hand air 45 gap, more flux being diverted through the first of these two shunt related paths from

the second of such paths as the right hand air gap increases and more being diverted through the second of such paths from the first as this right hand air gap decreases. The spacing intervening between the fulcrum 7 and the left hand air gap is selected 70 to enable the flux there to effect magnetic attraction as desired, the sum of the lines of force at the left hand air gap multiplied by their respective distances from the fulcrum 7 quickly becoming greater than a similar summation at the right hand air gap when the armature is being magnetically attracted. As soon as the armature moves the slightest owing to magnetic attraction a redistribution of the flux along the lines above set forth is immediately commenced and rapidly continues to insure a rapid and complete closing stroke of the armature after the initial unbalancing of the flux at the opposite ends of the armature occurs, the tendency of the armature 6 to continue the entire stroke upon which it has commenced being so strong that it will take its full movement even though the initial magnetizing force required to start the movement be largely reduced. 75

The strip metal springs 17 and 18 carry disk-shaped contacts 27, 28, the strip metal spring 25 engaging the spring 18 near the outer peripheral portion of the disk contact 28 for the purpose of so flexing the spring 18 as to enable the opposing faces of the contacts 27 and 28 to be in exact parallelism when the contact 27 is on the point of application to the contact 28 when the spring 17 carrying contact 27 is moved upwardly by the armature through the intermediation of the insulating post 24, whereby the adjacent faces of these contacts are initially in engagement throughout to prevent undue introduction of resistance at this point of contact. The stop 26 is adjustable to enable the spring 18 to be properly initially positioned, the stop 26 operating upon the spring 18 through the spring 25. The spring 17 carries a lower contact engaging the normal contact upon the spring 21. An adjustable post 23 limits the extent to which the spring 21 may be flexed upwardly due to its own resilience when the spring 17 is lifted. 80

The strut 12 is stamped out of sheet metal so as to be somewhat in the form of an H, the lower and smaller end of the strut passing through the opening 29 in the armature which is too small to permit the other end of the strut to pass through this opening, the smaller end of the strut then being passed through the opening 30 in the tongue 125 13 lengthwise of this opening whereafter the tongue and strut are turned 90° with respect to each other to cause the smaller end of the strut to lie crosswise of the narrower dimension of the opening 30. Thus 130

by a simple expedient the elements 6 and 13 are effectively coupled to enable the spring 8 to exert retracting pressure upon the armature, the extent of this retracting pressure being regulated by the wedging action which the screw 11 has upon the spring 8.

While I have herein shown and particularly described the preferred embodiment of my invention I do not wish to be limited to the precise details of construction shown as changes may readily be made without departing from the spirit of the invention, but

Having thus described my invention I claim as new and desire to secure by Letters

15 Patent the following:—

1. An electro-magnet having a swingingly mounted armature provided with a retractile spring, and a strut joining the armature and spring, the strut having a long narrow 20 head while the spring has an elongated opening of a size to permit said head to pass therethrough lengthwise of the opening and head but not with the head crosswise of the opening.

25 2. An electro-magnet having a swingingly mounted armature provided with a retractile spring, and a strut joining the armature and spring, the strut having a long narrow head while the spring has an elongated opening of a size to permit said head to pass therethrough lengthwise of the opening and head but not with the head crosswise of the opening, said strut having a second and 30 larger head engaging the armature that is provided with an opening permitting of the passage therethrough of the smaller strut head and preventing such passage of the larger strut head.

3. An electro-magnet having a swingingly mounted armature provided with a retractile spring held at both ends and carrying a tongue having its end which is free of the spring connected with the armature.

4. An electro-magnet having a swingingly mounted armature provided with a retractile spring held at both ends and carrying a spring tongue having its end which is free of the spring connected with the armature.

5. An electro-magnet having a swingingly mounted armature provided with a retractile spring held at both ends and carrying a tongue, and a strut connecting the armature

and the end of the tongue which is free of the spring.

6. An electro-magnet having a swingingly mounted armature provided with a retractile spring held at both ends and carrying a spring tongue, and a strut connecting the armature and the end of the tongue which is free of the spring.

7. An electro-magnet having a swingingly mounted armature provided with a retractile spring held at both ends and carrying a tongue having its end which is free of the spring connected with the armature, and 65 means for adjusting the position of the spring.

8. An electro-magnet having a swingingly mounted armature provided with a retractile spring held at both ends and carrying a 70 spring tongue having its end which is free of the spring connected with the armature, and means for adjusting the position of the spring.

9. An electro-magnet having a swingingly mounted armature provided with a retractile spring held at both ends and carrying a tongue, a strut connecting the armature and the end of the tongue which is free of the spring, and means for adjusting the position 80 of the spring.

10. An electro-magnet having a swingingly mounted armature provided with a retractile spring held at both ends and carrying a spring tongue, a strut connecting the armature and the end of the tongue which is free of the spring, and means for adjusting the position 85 of the spring.

11. An electro-magnet switch including two swingingly mounted contacts having 90 opposing engageable flat contact faces; an electro-magnet for swinging one of said contacts toward the other; a strip spring upon which the other contact is mounted; and means for flexing said spring to enable the 95 extended engagement of said contact faces upon the initial engagement of the contacts.

In witness whereof, I hereunto subscribe my name this 22nd day of April A. D., 1913.

ALBERT E. BERDON.
